UNITED STATES PATENT OFFICE.

THEODOR KUNDTZ, OF CLEVELAND, OHIO.

DESIGN FOR A SEWING-MACHINE COVER.

SPECIFICATION forming part of Design No. 17,415, dated June 28, 1887.

Application filed May 3, 1887. Serial No. 237,015. Term of patent 7 years.

To all whom it may concern:

Be it known that I, THEODOR KUNDTZ, a citizen of the United States, and residing in Cleveland, Cuyahoga county, State of Ohio, 5 have invented and produced a new and original Design for Sewing-Machine Covers, of which the following is a specification, reference being had to the accompanying drawing, forming a part thereof.

10 The figure is a view in perspective of my newly-designed sewing-machine cover:

The distinctive features of my design consist—

First, of a raised panel, A, on the front side 15 of the cover, the same being divided by ornamental lines into spaces, the two end spaces having carved work therein, as shown at a. The central portion of the panel is usually left blank for receiving the name of the sewing-machine. A border of grooved work is usually had on the panel, substantially as 20 shown; but I make no claim to such border.

Second, rounded upper edges, B, along the front and rear sides of the cover, with outward swell C and reverse curve D, both ex- 25

tending around the four sides of the cover. A small bead-molding, d, is at the center of the reverse curve; but this is not material.

What I claim is—

1. In a design for sewing-machine covers, 30 the ornamentation of the same, consisting, essentially, of a raised panel, the latter having the end portion ornamented with carved work representing a spray of leaflets with a banded quartering, as shown and described. 35

2. In a design for sewing-machine covers, the ornamentation of same, consisting of a raised panel, the end portions of which are ornamented with carved work, the said cover having rounded upper edges on its front and 40 rear sides and outward swells C and reverse curves D, both extending around the four sides of the cover, as described and shown.

In testimony whereof I sign this specification, in the presence of two witnesses, this 21st 45 day of April, 1887.

THEODOR KUNDTZ.
